MACHINE FOR AND METHOD OF MAKING
KNITTED ARTICLES

Virgil Morris, Daisy, Tenn., assignor to Richmond Hosiery Mills, Rossville, Ga., a corporation of Georgia

Application September 17, 1935, Serial No. 40,942

5 Claims. (Cl. 66—9)

My invention relates to knitted articles, and more particularly to improvements in knitted socks, stockings, dresses, underwear, and the like, and to the method of weaving, floating, or otherwise inserting into the knitted article, rubber or "Lastex" thread, or in making rubber or "Lastex" thread a part of such article by an improved machine.

It has been the practice in the prior art to use rubber, "Lastex," elastic or other material which stretches in a knitted article to hold it in place on the body, when such article is being worn.

In the case of socks and stockings such lastex, rubber, etc. is made a part of the top in a ribbing machine while the other parts thereof are knitted in the regular plain knitting machine, then by a separate operation the top is joined to the body of the sock or stocking through what is known as the "loose course" or "transfer line". Each of these operations requires additional equipment, added labor, and reduces the output, thereby resulting in added expense and increased cost of production.

It has been suggested that the tops be eliminated, and the whole article be made in a single machine where the elastic material may be formed into the article as it is made by such machine. As such operation comprehends that the elastic will be knitted into the article along with the yarn, it is necessary for the needles of the machine to grab or catch the elastic material in the hooks and form stitches with it in the yarn of the article, and in so doing they cut or otherwise injure it and reduce its useful life. In some cases the elastic material is entirely broken by the hook, with resulting delay and reduction of production.

Articles made by the above method will contain elastic material stitched therein about once every four or five welts of yarn. This permits the formation of loops of elastic material extending around the inner circumference or wall of the article and permits the toe nails of the wearer to be caught therein, and break such material in putting on or removing the article with consequent annoyance. These loops of elastic material give an uneven contracting of the article about the wearer's body, and an unsightly puckering or bulging into pleats. Such loops also permit of easy breaking when washing the article.

A knit in elastic also lends itself to many other disadvantages. The stitches made with the yarn of the article retards or prevents relative movement between the yarn and the elastic material so that localized stress cannot be accommodated

by an increased supply of elastic material over such area.

Applicant, with a knowledge of these facts, has, as an object of his invention, the overcoming of the above objections and defects by producing an article containing elastic material, which bears a different relation to the knitted yarn of the article, than has been known by laying or floating the elastic material into the material of the article by a new and novel process.

The method is carried out by using the regular plain knitting machine as it is used to form the other parts of the sock or stocking or other garment. It comprehends raising every odd, or every other, needle of said machine (where the flat top revolving cylinder machine is employed) to such a height that a finger in what is here called the latch ring feeds "Lastex" or rubber thread there-to below the latch of said raised needle, where-upon each raised needle is lowered and as the normally positioned needles are slightly raised the thread falls behind said normally positioned needles, then yarn is fed to the hooks of all of the needles over the elastic thread, and the needles, in their knitting operation of drawing the new yarn through the old loops on their bodies, shed the elastic thread over their tops and such thread is formed into the knitted material by a float about each stitch of yarn in said article.

This eliminates the necessity for the use of a ribbing machine and the separate operation of joining the ribbed element to the body of the sock or stocking, with a resulting increased production at a reduced cost and some saving of material. It also prevents cutting of or injuring the elastic material by the hooks of the needles ordinarily employed to knit the elastic material with the yarn.

The article resulting from this process contains elastic material of longer life in virtue of being woven or floated into such intimate relation with the material of the article that it can hardly be noticed, and certainly is not subject to severance or breakage by the wearer while removing it or putting it into place. The elastic will also be free to move with respect to the strands of yarn of the article to remove points of stress, and thus produce a constant and well distributed stretching of the elastic material throughout its length, serving to increase its life.

The invention will be clearly understood from the following description when read in connection with the attached drawing, of which the figure shows a needle cylinder slit and rolled out flat with all of its associated elements.

Referring to the drawing in detail, the figure shows a cross-sectional view of a portion of a flat top revolving cylinder type knitting machine, where a cylinder is adapted to rotate about a vertical axis, and having longitudinal grooves formed around its entire outer circumference into which needles 12 are slidably fitted, and also slidably seated in every other groove beneath each odd needle is a jack 13 for raising its accompanying needle. Each of said needles 12 are bowed (not shown) to provide a friction fit in its groove so that such needle will remain in the position where it is placed or moved without auxiliary support, but the jacks are loosely fitted into the grooves and must always be supported by additional means when in raised position.

At the top thereof each needle is formed with a hook 16 and just below the hook and to the body of the needle is secured a latch 17. Adjacent the bottom of each needle 12 is formed a lug 14, and at the bottom of each jack 13 is formed a like lug 15. The purpose of these lugs is to engage cams mounted on the stationary part of the machine for raising or lowering such needles or jacks in a manner to be more clearly described herein-after.

d designates what may be called a latch ring employed to prevent the latches 17 on the needles from rising and covering the hooks when the needles are in raised or normal position. *g* designates a finger for feeding "Lastex" or rubber thread to the needles, and *h* designates a finger for feeding yarn for the same purpose. The clipping means for cutting the "Lastex" or yarn at the point where it is no longer desired to feed such yarn or "Lastex" has not been shown as it is standard equipment and acts in its well known and usual way. *a* designates a stationary jack cam of greater height than that ordinarily employed and acts to raise the jacks through their lugs 15, and to raise their corresponding needles to a position where the finger *g* may feed "Lastex" or rubber thread *2* below the latch on each of said needles. *b* designates a stationary cam, shown in dotted lines, which acts upon the lugs 14 of the raised needles to lower them. *c* designates a stationary cam, dotted in, which acts upon lugs 14 of the normally positioned needles, that is, the even needles which have no jacks under them, for slightly raising them. *e* designates a stationary cam, dotted in, for successively lowering all of the needles when such point has been reached in the revolution, by acting on their lugs 14. *f* designates a stationary cam, dotted in, for successively lowering the needles still further by acting on their lugs 14, and *g* designates a stationary cam, dotted in, for finally restoring each of the needles to normal position.

The operation of the machine and the process of inserting "Lastex" or rubber thread while making the article is as follows:

In the position shown each of the needles 12 has a loop of yarn 1 around the body thereof, and the needles are moving as a part of the revolving cylinder 11 in the direction indicated by the arrows in the figure.

Beginning at the extreme right it is seen that every odd needle 12 is being gradually raised by its corresponding jack 13 since in their movement they are riding up the wall of the stationary jack cam *a*, while the adjacent even needles remain at their normal position unaffected by said jack cam as they ride over it. The odd needles finally reach their ultimate height as they successively pass the point where the finger *g* feeds "Lastex"

or rubber thread *2* under the latch 17 but over the heads of the normally positioned needles. All of the needles then successively pass to the cams *b* and *c* where the raised needles are gradually forced downwardly by the cam *b* and the normally positioned needles are slightly raised by the cam *c*, which engage the lugs 14 on said needles. By this operation the "Lastex" or rubber thread previously fed under the latches of the raised needles is placed behind the hooks of the adjacent normally positioned needles on their back side away from the latches.

After this the needles move on and all are forced downwardly by the action of the stationary cam *e* acting on the lugs 14 as they ride over the surface of such cam, during which operation yarn is fed to the hooks of all of the needles over the "Lastex" or rubber thread by the finger *h*.

During all of these operations the latches of the needles are maintained in lowered position by cam ring *d*.

The needles then pass successively to stationary cam *f* where they are again forced downwardly by the operation of said cam on the lugs 14 of the needles as they traverse the surface thereof. As such needles are lowered by cam *f* they successively clear the cam ring *d* so that the loops of yarn in this relative movement force the latch members 17 upwardly to place a closure across the hooks and retain the newly fed yarn trapped therein. As the needles are depressed still further by the action of the cam *f* the "Lastex" or rubber thread, in the case of the odd needles, slides off of the closed latch over the head of each of said needles, and in the case of the even needles, the "Lastex" or rubber thread slides off of the backs of the needle hooks in leaving each of those needles, and such thread is by this action floated or woven into the knitted article, as the needles in being further depressed pass through the old loops of yarn, shed them from their body, and pull the new yarn trapped in their hooks through the old loops along with them thereby forming a new loop each time a needle reaches the lower extremity of cam *f*. The needles then successively pass to stationary cam *g* where they are raised by its action on the lugs 14 as they ride over it. The cam *g* raises such needles to their normal position and such operation forces the newly formed loop of yarn 1 down with the opening latch and over it, onto and around the body of the needle, thus completing a cycle in the operation of the machine, so that they may again pass on for the action of the jack cam *a*. This cycle is repeated again and again until the operation is completed.

"Lastex" or rubber thread may be inserted in only a part of the circumference of the knitted article by only feeding it to a limited number of needles each cycle, and such thread may be laid into only every second, third, etc. welt of the knitted article by raising every third, fourth, etc. needle by the jack cam *a* instead of every other needle.

While the method here described is presented in connection with a flat top revolving cylinder knitting machine, it is not to be considered to be limited thereto.

Having thus described my invention, I claim:

1. The method of incorporating elastic thread into a knitted article comprising rotating a ring of knitting needles, successively raising each of a plurality of said needles, feeding said thread below the latch of each of the raised needles, successively lowering said raised needles while

raising normally positioned needles to place the thread behind said normally positioned needles, lowering each of said needles, feeding yarn to their hooks, and successively lowering each of said needles still further to knit the yarn and incorporate the elastic thread in the fabric.

2. A method of incorporating elastic thread into a knitted article comprising successively raising each of a plurality of needles of a circular 10 series, feeding said thread below the latch of each of the raised needles, successively lowering said raised needles while raising normally positioned needles, lowering each of said needles and feeding yarn to their hooks, and successively 15 lowering each of said needles still further to knit the yarn and incorporate the elastic thread in the fabric.

3. A method of incorporating elastic thread into a knitted article comprising successively raising each of a plurality of needles of a circular series, feeding said thread below the latch of each of the raised needles, successively lowering said raised needles while raising normally positioned needles, feeding yarn to the hooks of each of said needles, and successively lowering each of said needles to knit the yarn and incorporate the elastic thread in the fabric.

4. A knitting machine for incorporating elastic thread into a knitted article comprising a needle

cylinder having a circular series of independent needles, cam means for successively raising a plurality of said needles, means for feeding said thread below the latch of each of the raised needles, cam means for successively lowering 5 each of said raised needles and raising normally positioned needles to place the thread behind said normally positioned needles, cam means for lowering each of said needles, means for feeding yarn to their hooks, and cam means for successively lowering each of said needles to knit the 10 yarn and incorporate the elastic thread in the fabric.

5. A knitting machine for incorporating elastic thread into a knitted article comprising a needle 15 cylinder having a circular series of independent needles, cam means for successively raising each of a plurality of said needles, means for feeding said thread below the latch of each of the raised needles, cam means for successively lowering 20 each of said raised needles and raising normally positioned needles to place said thread behind said normally positioned needles, means for feeding yarn to the hooks of each of said needles, and cam means for successively lowering each 25 of said needles to knit the yarn and incorporate the elastic thread in the fabric.

VIRGIL MORRIS.
